US0D1103971S

(12) **United States Design Patent** (10) **Patent No.:** **US D1,103,971 S**
(45) **Date of Patent:** **** Dec. 2, 2025**

(54) **EARPHONE**

(71) Applicant: **Apple Inc.**, Cupertino, CA (US)

(72) Inventors: **Robert Boyd**, Los Angeles, CA (US); **Sean Stewart Corbin**, South Lake Tahoe, CA (US); **Duy P. Le**, Venice, CA (US); **Guillaume Raoult**, San Francisco, CA (US); **Christopher Kuh**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/996,222**

(22) Filed: **Mar. 31, 2025**

Related U.S. Application Data

(63) Continuation of application No. 29/936,082, filed on Apr. 5, 2024, now Pat. No. Des. 1,068,741, which is a continuation of application No. 29/894,352, filed on Jun. 8, 2023, now Pat. No. Des. 1,021,867, which is a continuation of application No. 29/853,397, filed on Sep. 15, 2022, now Pat. No. Des. 990,458, which is a continuation of application No. 29/825,907, filed on Feb. 7, 2022, now Pat. No. Des. 964,324, which is a continuation of application No. 29/776,667, filed on Mar. 31, 2021, now Pat. No. Des. 942,971, which is a continuation of application No. 29/721,504, filed on Jan. 21, 2020, now Pat. No. Des. 916,057, and a continuation of application No. 29/721,503, filed on Jan. 21, 2020, now Pat. No. Des. 916,056, which is a continuation of application No. 29/685,002, filed on Mar. 25, 2019, now Pat. No. Des. 897,320.

(57) **CLAIM**

The ornamental design for an earphone as shown and described.

DESCRIPTION

FIG. 1 is a front perspective view of an earphone showing the claimed design;

FIG. 2 is a bottom front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines in the figures show portions of the earphone that form no part of the claimed design.

1 Claim, 4 Drawing Sheets
